UNITED STATES PATENT OFFICE.

HARRISON D. FLEGEL, OF RACINE, WISCONSIN.

DRINK MIXER.

Application filed January 25, 1929. Serial No. 334,945.

This invention relates to improvements in mixers and more particularly to drink mixers.

One of the objects of my invention is the provision of a drink mixer provided with novel means for applying and shutting off the driving power for the agitator whereby the agitator may be readily rotated after being received into the receptacle and the driving power readily cut off before removing the agitator from the receptacle.

Another object of my invention is the provision of new and improved means for mounting the driving mechanism so that parts thereof may be actuated at the will of the operator for imparting movement to the agitator and includes means whereby the agitator is simultaneously moved with the movable parts of the driving means so that the agitator may be raised and lowered relative a receptacle.

A further object of the invention is the provision of a drink mixer which is provided with movable means for supporting a portion of the driving mechanism and additional means is provided for raising and lowering the first means at the will of the operator so that the agitator may be driven when so desired.

With the above and other objects in view, the invention consists in the novel features of construction, the combination and arrangement of parts hereinafter more fully set forth, pointed out in the claims and shown in the accompanying drawings wherein:

Figure 1 is a vertical sectional view of my improved mixer, parts thereof being illustrated in elevation;

Figure 2 is a side elevation;

Figure 3 is a section on the line 3—3 of Figure 1;

Figure 4 is a transverse section on the line 4—4 of Figure 3;

Figure 5 is a detailed section on the line 5—5 of Figure 3.

In carrying out my invention, I preferably use the same in connection with a motor 1, mounted upon a stationary platform 2, said motor having upon its driving shaft a pulley 3.

Extending upwardly from the base member 2 are the spaced standards 4 upon which is slidably mounted the housing 5 enclosing the pulley 3 and provided in its rear wall with a vertical slot 6 to receive the drive shaft of the motor 1.

The housing 5 is provided with a lateral extension 7 having a removable top plate 8

and a lower bearing sleeve 9. The top plate 8 is retained in place by means of set screws 10 and 11, the screw 10 passing through the top plate 8 and engaging within a threaded opening formed in the outer wall of the housing 7. The screw 11 passes through an upstanding flange on the top plate 8 and engages the upper portion of the housing 5.

Supported within the housing 5 at the inner end of the housing 7 is a bracket 12 supporting a shaft 13 having upon each end a pulley 14. The housing 7 encloses a pulley 15, the shaft 16 of which is rotatably mounted in the bearing sleeve 9 and this pulley 15 is connected with the pulley 3 by means of a belt 17 which passes over the pulleys 14 as the pulleys 3 and 15 are disposed at right angles to each other, thus necessitating the turning of the belt as it passes over one pulley to the other, this turning movement being imparted to the belt by having the same passing over the pulleys 14.

The housing 5 has at its lower end a laterally projecting shelf part 18 which extends outwardly from the front wall of the housing and extending upwardly from this shelf are the spaced guide rods 19, the upper ends of which are received in suitable sleeves 20 carried by the housing 7.

The machine is particularly designed for use in mixing drinks and particularly drinks where the fluid body is comparatively heavy or thick and for this purpose I provide a comparatively heavy cup-like receptacle 21 having a handle 22 at one side, and a heavy flanged bottom 23, the flange on the bottom extending a short distance beyond the side wall of the cup. On the lower end of the shaft 6, I mount an agitator which is in the form of a yoke 24 having a connecting cross piece 25 for the ends of the yoke.

The shaft 16 is surrounded by an elongated bearing sleeve 26 upon which is slidably mounted a sleeve 27, closed at its lower end and carrying a disc like shield member 28, which is used for closing the cup 21 when in its operative position as shown in Figure 1.

In order to normally urge the shield member 28 downwardly upon the shaft 16, a coil spring 29 is mounted upon the shaft 16 within the sleeve 27 and disposed between the lower end of the elongated bearing sleeve 26 and the lower closed end of the sleeve 27.

From this, it will be apparent that when the shield 28 is disengaged from the walls of the cup, the spring 29 will force the same

downwardly until the pin 30 carried thereby engages with the yoke 24, and as the yoke 24 is rotated with the shaft 16, the shield 28 will also be rotated with the agitator.

5 In order to support the cup 21 in an operative position for mixing a drink, I provide a tilting plate like member 31 which has lugs 32 upon its lower edge mounted within suitable recesses in the transverse plate 33 attached to the inner side of the front wall of the housing 5.

This plate 31 is normally maintained in an upright position by means of the spring 34 on the pin 35, the pin being carried by 15 the plate 33 and the spring 34 being disposed between the plate 31 and the head of the pin as illustrated in Figure 4, so that the tension of the spring will maintain the plate 31 in its normal position.

20 Extending laterally from the upper edge of the plate 31 and passing through an opening in the front wall with its outer end projecting beyond the front wall, is a stop member 36 which has a lower cam like face 37, 25 the upper face of the stop being preferably disposed in a horizontal plane. From this it will be apparent that when the cup is moved upwardly for engaging the shield 28 with the inner wall of the cup, the flanged 30 bottom of the cup will contact the cam face 37 rocking the plate 31 to permit the flange to pass upwardly above the stop member 36, and as the flange passes the stop 36, the spring 34 will return the stop to its normal 35 position as shown in Figure 1, to form a rest for the cup. When it is desired to release the cup, the plate 31 is manually rocked upon its pivot by engaging a thumb piece 38 on the outer end of a pin 39, which extends through an opening in the front wall 40 of the housing 5 and is engaged with the plate 31 to rock the same upon its pivot.

It will be apparent that in placing the cup 21 in position, the cup is moved inwardly 45 until it engages the guide rods 19 and as the cup moves upwardly, the lower end of the same is pushed inwardly until the flange bottom contacts with the guide members so that this flange will engage the stop 36 and pass 50 above the same as described above.

In Figure 1, I have illustrated the device as in an operative position, and in Figure 2, I have illustrated the device in an inoperative position in dotted lines.

55 When the device is in an inoperative position as shown by the dotted lines of Figure 2, the belt 17 is in a slack condition so that it does not engage the pulley 3 and no movement is imparted to the pulley 15, shaft 16 and the agitator, this being carried out by raising and lowering the housing 5. This raising and lowering operation is performed by having the hand lever 40 pivoted on the pin 41 which is carried by one of the standards 60 65 4, a slot 42 being formed in the wall of the

housing 5 to permit the housing to move relative the pin. The lever 40 is fulcrumed on the pin 41 and one end of the lever is pivotally connected as at 43 to link 44, the lower end of the link being pivotally connected to the 70 housing 5 as shown in 45.

The outer end of the lever 40 is provided with a handle 46 which may be grasped by the hand of the operator for rocking the lever upon its pivot.

75 It will be apparent that when the device is in an inoperative position, the parts are positioned as illustrated by the dotted lines in Figure 2 with the lever 40 and the link 44 lying parallel with the housing 5, this position drops the lower loop of the belt 17 downwardly from engagement with the pulley 3. After the cup has been placed in an operative position as shown in Figure 1, with its flanged bottom resting on the stop 36 and the shield 28 engaged with the inner wall of the cup, the housing 5 is moved upwardly by grasping the handle 46 of the lever 40 and pulling the lever 40 downwardly to the position shown in Figure 2, this movement of the lever exerting 80 an upward pull on the lever 44, which in turn will move the housing 5 upwardly, the slot 42 permitting the housing to move relative the pin 41 and tightening the belt 17 so that the same will be brought into engagement with the pulley 3 to impart a rotative movement to the shaft 16 and the agitator 85 within the cup.

90 During the mixing of the contents of the cup 21, the lever 40 is maintained in its operative position by the operator and after the drink has been properly mixed the lever 40 is moved back to its inoperative position shown by the dotted lines in Figure 2, this movement moving the housing 5 outwardly 95 to disengage the belt 17 from the pulley 3.

100 During the mixing of the drink some of the ingredients will have a tendency to adhere to the lower face of the disc like shield 28 and in order to remove these particles, the cup is dropped downwardly until its flanged bottom rests upon the shelf 18, this operation being carried out by pushing inwardly on the pin 39 to release the stop 36 from the bottom of the cup. The cup having been dropped 105 downwardly on the shelf 18, the shield 29 will be positioned upwardly in the cup so that it will not engage the walls thereof and the coil spring 29 will move the shield downwardly until the pin engages the yoke 24. The shield 110 may then be rotated at a high rate of speed by pulling the lever downwardly to impart movement to the shaft 16 and the agitator which in turn will rotate the disc 28.

115 From this, it will be apparent that the particles adhering to the lower face of the disc 28 may be removed before the cup is entirely removed from the device.

I claim:

1. In a drink mixer, a support, a movable 120

- housing carried by the support, a rotatable shaft carried by the housing, an agitator on one end of the shaft, a pulley on the other end of the shaft, a power driven pulley stationary relative the housing, a belt connecting the two pulleys, manually controlled means for imparting movement to the housing whereby to engage and disengage the belt with the stationary pulley.
5. In a drink mixer, a stationary support, and lower the housing relative the support. a movable housing carried thereby, a receptacle support carried by the housing and including a pivotally mounted plate, a stop member carried by the plate, and projecting through one wall of the housing, with one face thereof normally disposed in a horizontal plane, means for urging the plate to a normal position and means whereby to manually actuate the plate to move the stop member from its normal position.
10. 2. In a drink mixer, a movable housing, a stationary power driven pulley therein, a shaft movable with the housing, an agitator carried by the shaft, a pulley on the shaft, a belt connecting the movable and stationary pulley and means for imparting movement to the housing to engage the belt with the stationary pulley or disengage the same therefrom.
15. 3. In a drink mixer, a stationary support, a movable housing carried thereby, a power driven pulley arranged in the housing, a rotatable shaft carried by the housing, an agitator on one end of the shaft, a pulley on the other end, means for supporting a receptacle adjacent the housing to receive the agitator, a belt connecting the two pulleys, manually controlled means for imparting movement to the housing whereby to engage the belt with the stationary pulley or disengage the same therefrom.
20. 4. In a drink mixer, a stationary support, a movable housing carried thereby, having a slot in one wall, a pin carried by the stationary support and projecting through the slot, a lever fulcrumized on the pin, and a link having one end connected to the lever and the other end connected to the housing whereby movement of the lever will raise
25. 5. In a drink mixer, a stationary support, a movable housing carried thereby, means for imparting movement to the housing relative the support, a laterally projecting shelf member at the lower end of the housing, vertically disposed spaced guide rods extending upwardly from the shelf member, and sleeves carried by the housing to receive the upper ends of the guide rods.
30. 6. In a drink mixer, a stationary support, a movable housing having a lateral extension, a rotatable shaft depending from the extension, an agitator on the lower end of the shaft, a pulley on the upper end of the shaft in the extension, a stationary power driven pulley arranged in the housing, a belt connecting said pulleys and manually controlled means for imparting movement to the housing whereby to engage the belt with the stationary pulley or disengage the same therefrom to control the movement of the agitator.
35. 7. In a drink mixer, a stationary support, a movable housing having a lateral extension, an agitator on the lower end of the shaft, a pulley on the upper end of the shaft in the extension, a stationary power driven pulley arranged in the housing, a belt connecting said pulleys and manually controlled means for imparting movement to the housing whereby to engage the belt with the stationary pulley or disengage the same therefrom to control the movement of the agitator.
- In testimony that I claim the foregoing I have hereunto set my hand at Racine, in the county of Racine and State of Wisconsin.

HARRISON D. FLEGEL.
